BOTTLE FILLER

Carl A. Namur, Kenosha, Wis., assignor to
Specialty Brass Company, Incorporated, Kenosha, Wis., a corporation of Wisconsin

Application October 20, 1937, Serial No. 170,104

9 Claims. (Cl. 226—124)

This invention relates to a bottle filler and the apparatus is especially useful in connection with a milk bottle filling machine. Other uses will be obvious.

5 An object of the invention is to provide a bottle filler of simple construction by which milk bottles and the like can be readily filled without overfilling and without any drippage of liquids from the valve, the valve mechanism functioning automatically in the release of air from the bottle as the bottles are filled, then sealing the bottle against overfilling, and then permitting the inrush of air to release the vacuum after the bottle is filled. Other specific objects and advantages will appear as the specification proceeds.

The invention is illustrated, in a preferred embodiment, by the accompanying drawings, in which—

Figure 1 is a broken vertical sectional view of 20 an apparatus embodying my invention, the valve being shown in closed position; Fig. 2, an enlarged transverse sectional view illustrating a detail of the apparatus; Fig. 3, a view similar to Fig. 1 but showing the air valve in open position; Fig. 25 4, a bottom plan view of the valve structure, the view being taken as indicated at line 4 of Fig. 3; and Fig. 5, a view similar to Fig. 1 but showing the valve in fully opened position.

In the illustration given, A designates a milk 30 vat or tank equipped with the usual inner lining A', the tank being a part of a filling machine and normally equipped with a number of discharge valves. For the purpose of description, it is believed unnecessary to describe, however, 35 but one valve. As shown in the drawings, the tank A is provided with an opening 10 in which is threadedly secured a sleeve 11, the lower portion of the sleeve being engaged by a nut 12.

Slidably supported within the sleeve 11 is a 40 hollow valve stem 13 which is provided at an intermediate position with oppositely arranged inlet openings 14. Above the inlet openings 14 extends a seat portion 15 which seals the openings from the interior of the tank when the valve stem 45 is in the closed position illustrated in Figs. 1 and 2. The valve stem is equipped at its lower end with a flange 16 equipped with four ears 17 having inwardly extending lug portions 18. The stem is also provided on its inner side with an inwardly 50 extending flange 19 providing a constricted outlet. At its upper end, the valve stem 13 is provided with a cylindrical extension 20 provided interiorly with a seat 21 in which is supported a washer 22. A cotter pin 23 extends through the

cylindrical extension 20 and frictionally engages an air tube 24.

The air tube 24 is provided at its lower end with outwardly flared sides 25 which engage the ends of the flange 19 of the valve stem 13 so as to effectively seal the lower end of the valve stem 13. At its upper end, the air tube is provided with oppositely disposed rectangular air spaces 26. As shown more clearly in Fig. 1, the air tube 24, when the valve is in closed position as shown 10 in Fig. 1, has its upper end spaced below the top of the vat and can therefore move freely upward with the valve stem for a limited distance.

An air valve plug 27 is normally supported in fixed position so as to seal the air tube 24 when 15 it is in lowermost position. The frustoconical plug is carried by the valve plug stem 28 secured to a cross strip 29 with which the tank A is equipped by spring means which normally maintains the plug in fixed position but which, in case 20 of emergency, permits a yielding of the plug so as to prevent injury to the machine or to a bottle caught thereunder. The upper end of the stem 28 is secured in an enlarged plug 30 by means of short pins 31. The upper end of the plug 30 is 25 apertured to receive an end portion 32 of a spring 33, the other end of the spring 33 being passed through an aperture 34 within a fitting 35 carried by the cross piece 29. By this means, the stem 28 is normally held in fixed position so that plug 30 30 32 does not move. In the case of an accident, however, where a bottle should be thrust against the plug, the plug is permitted to yield, thus protecting the bottle and the apparatus.

In order to effect a seal with the bottle and 35 also to provide means for breaking the vacuum created when the bottle is about to be withdrawn from the filler, I prefer to provide a resilient sealing member 36 for enclosure within the space provided by the ears 17 and flange 16. The annular sealing member 36 of rubber or other suitable material is preferably provided with a tapered inner lip member 37 which follows the flange portion 19 of the valve stem 13 and also provides a chamber 38 between the seal and the flange 16. 40 The chamber 38 provides a space for receiving air which may be released to break the vacuum when the bottle is to be removed. It will be noted that the seal 36 is suspended upon the ear portions 18 and is moved upward against the flange 16 when 45 engaged by a bottle 39. A coil spring 40 is located between flange 16 and the nut 12 and tends to urge the valve stem 13 downwardly to the closed position shown in Fig. 1.

In the operation of the device, a bottle 39 is 55

supported upon the usual platform provided in a filler machine, and the platform is raised so as to press the upper open end of the bottle neck against the seal 36. Prior to the engagement of 5 the seal 36 with the bottle 39, the valve parts are in the position shown in Fig. 1, the plug 27 sealing the lower end of the air tube 24 and the flared mouth 25 of the air tube closing the lower constricted end of the valve stem 13. Engagement 10 with the bottle 39 causes the seal 36 to be lifted against the flange 16 and the valve stem 13 is raised to the position shown in Fig. 3, the air tube 24 being raised also because of its frictional engagement with cotter pin 23, thus opening the air 15 tube at its lower end. Air may now pass from the bottle freely through the tube 24 and out through the apertures 26 at the top of the tube. In this position, it will be noted that the upper end of the air tube 24 has now struck the spring 20 arm 32 which prevents further upward movement of the air tube. Continued upper pressure by the bottle causes the valve stem 13 to leave the lower flared end 25 of the air tube and to reach the fully 25 opened position shown in Fig. 5. In this position, the liquid within the tank A may pass through the openings 14 into the interior of the stem 13, thence outwardly through the open end of the stem into the bottle.

If the platform remains raised sufficiently long 30 enough, the bottle is filled. If it remains raised only a short time, the bottle will be partially filled. In normal practice, the platform remains raised long enough to fill a pint bottle, but only long enough to half fill a quart bottle. In the case of 35 a quart bottle, the platform either raises the same bottle to the same valve or moves it to a second valve of similar construction to complete the filling. Overfilling is prevented by engagement of the bottle neck with the seal 36 which confines 40 the liquid within the valve stem and the bottle.

In the upward movement of the bottle, the seal 36 is first pressed against the flange 16 while still providing a chamber 38 which is open to the interior of the bottle. However, as the bottle is 45 moved upwardly to the position shown in Fig. 5, the lip 37 of the seal 36 is pressed tightly against the flange 19. This pressure serves to close the chamber 38, substantially sealing the chamber and the air contained therein from communication 50 with the interior of the bottle. Normally when the bottles are filled in filling machines, a certain amount of vacuum is created in the bottle top, this vacuum being sufficient if no means of breaking it were provided, to cause the bottles 55 to adhere tightly to the filler valve or seal. In the present case, when the bottle is being withdrawn, the lip 37 of the seal 36 permits the air within chamber 38 to be released and this serves to break the vacuum, thus permitting the bottle 60 to break away cleanly from the seal 36.

It will be observed that the timing of the valve can be modified considerably by changing the length of the tube 24, thus increasing or decreasing the distance between the top of the 65 seat 15 and the spring 32. Also, the length of the seat 15 can be modified so as to hasten or retard the filling of the stem 13. In the operation of the valve, the floating valve 36 serves to completely seal the stem with the bottle so as to prevent overfilling of the bottle while at the 70 same time preventing any drippage of liquid from the valve while the bottles are being changed or, in fact, at any time while the valve is in closed position.

75 The spring 33, while ordinarily maintaining

the stem 28 and plug 27 in a fixed position relative to the air tube and valve stem, permits upward movement of the stem 28 and plug 27 in case of accidental misplacement of bottles, etc. so as to prevent injury thereto and to the filler apparatus. 5

While in the description given, I have shown but a single filler valve, it will be understood that the filler tank A will be ordinarily equipped with a number of such valves and that also platform means of regular and known construction will be 10 employed for raising and lowering the bottles and rotating them to bring them under various valves, this apparatus being old and well known in the art and no detailed description thereof being necessary. 15

While in the specification given, I have shown a single valve structure in detail for the purpose of illustration, it will be understood that the principles disclosed with respect to such structure may be embodied in different forms without departing from the spirit of my invention. The foregoing detailed description has been given for clearness of understanding only, and no unnecessary limitations should be understood therefrom, but the appended claims should be construed as 25 broadly as permissible, in view of the prior art.

I claim:

1. In combination with a liquid tank equipped with a discharge sleeve, a hollow valve stem guided in said sleeve, said stem having apertures 30 adapted to communicate with said tank when the stem is raised, means closing the upper end of said valve stem, an air vent tube passing through said last mentioned means and frictionally engaged thereby, said tube being supported for a 35 limited vertical movement, means carried by said air tube for closing the lower end of said valve stem when the latter is in lowermost position, and resiliently supported means for normally closing said air tube when in lowermost position. 40

2. In combination with a valve stem equipped at its lower end with a flange, a resilient seal supported by said flange and providing therewith an air chamber closed from communication with the interior of a bottle applied to said seal, 45 said resilient seal having a lip portion adapted to yield under the weight of said bottle to open the contents of said chamber into communication with the interior of the bottle.

3. In combination with a hollow valve stem 50 equipped at its lower end with a flange, means for breaking the vacuum within said stem when a bottle is withdrawn therefrom, said means comprising a resilient seal providing with said flange an air chamber closed from communication with the interior of said stem and having a tapered 55 lip portion adapted to yield when said bottle is partially removed to open said chamber into communication with said stem.

4. In combination with a liquid tank provided 60 with a discharge sleeve, a hollow valve stem guided therein and provided at its lower end with a flange, an air tube within said sleeve, substantially fixed means for closing the end of said tube at its lowermost position, means carried 65 by said air vent tube for closing said valve stem when in lowermost position, and a flexible resilient seal adapted to be engaged by the neck of a bottle and providing with said flange an air chamber closed from communication with the 70 interior of the bottle, said seal serving to open said chamber when tension is exerted thereon by the partial withdrawal of said bottle.

5. In combination with a liquid tank provided 75 with a sleeve equipped discharge opening, a hol-

- low valve stem guided in said sleeve, a fixed plug stem supported in said sleeve, a plug carried by said plug stem and normally closing said air tube when the latter is in lowermost position, 5 said air tube also serving to close said valve stem, a flange carried by said valve stem, inwardly extending ears supported in spaced relation by said valve stem, a movably supported resilient seal extending about said valve stem and movably supported by said ears, said seal being cut away 10 to provide an air chamber closed from the interior of a bottle applied to said seal between it and said flange, and spring means normally urging said valve stem toward lowermost position. 15
6. In combination with a liquid tank equipped with a discharge sleeve, a hollow valve stem guided in said sleeve, said stem having apertures adapted to communicate with said tank when 20 the stem is raised, means closing the upper end of said valve stem, an air vent tube passing through said last mentioned means, said tube being supported for a limited vertical movement, means carried by said air tube for closing the 25 lower end of said valve stem when the latter is in lowermost position, and means for normally closing said air tube when in lowermost position.
7. In combination with a liquid tank equipped with a discharge sleeve, a hollow valve stem guided in said sleeve, said stem having apertures adapted to communicate with said tank when the stem is raised, means closing the upper 30 end of said valve stem, an air vent tube passing
- through said last mentioned means and connected therewith for relative movement, said tube being supported for a limited vertical movement, means carried by said air tube for closing the lower end of said valve stem when the latter 5 is in lowermost position, and means for normally closing said air tube when in lowermost position. 10
8. In combination with a liquid tank equipped with a discharge sleeve, a hollow valve stem guided in said sleeve, said stem having apertures 15 adapted to communicate with said tank when the stem is raised, means closing the upper end of said valve stem, an air vent tube passing through said last mentioned means, said tube being supported for a limited vertical movement, means carried by said air tube for closing the lower end of said valve stem when the latter is 20 in lowermost position, and resiliently supported means for normally closing the air tube when in lowermost position. 25
9. In combination with a liquid tank equipped with a discharge sleeve, a hollow valve stem guided in said sleeve, said stem having apertures adapted to communicate with said tank when the stem is raised, means closing the upper end of 30 said valve stem, an air vent tube passing through said last mentioned means, means carried by said air tube for closing the lower end of said valve stem when the latter is in lowermost position, and means for normally closing said air tube when in lowermost position.

CARL A. NAMUR.
